UNITED STATES PATENT OFFICE.

ADAM E. CLUTE, OF WEST TROY, NEW YORK.

CHIMNEY-CAP.

SPECIFICATION forming part of Letters Patent No. 394,337, dated December 11, 1888.

Application filed August 20, 1888. Serial No. 283,227. (No model.)

To all whom it may concern:

Be it known that I, ADAM E. CLUTE, a resident of West Troy, in the county of Albany and State of New York, have invented certain new and useful Improvements in Chimney-Caps; and I do hereby declare that the following is a full, clear, and exact description of the invention, that will enable others skilled in the art to which it appertains to make and use 10 the same, reference being had to the accompanying drawings, and to the letters of reference marked thereon, which form a part of this specification.

Similar letters refer to similar parts in the 15 several figures therein.

My invention relates to improvements in chimney-caps; and it consists of the novel construction and combination of parts hereinafter described, and pointed out in the 20 claims.

Figure 1 of the drawings is a side elevation of a chimney top and cap in position thereon. Fig. 2 is a top plan view of same. Fig. 3 is a central vertical section of the chimney and 25 cap, taken on broken line $x-x$ in Fig. 2. Fig. 4 is an inside plan view of one of the corner-pieces detached. Fig. 5 is a plan view of a sheet-metal blank adapted to be bent on two sides to form one side of the chimney-cap. Fig. 6 is a plan view of one side of the cap 30 detached and formed from the blank shown in Fig. 5. Fig. 7 is a plan view of four sides of a cap in different sizes detached and packed one within another in the manner of packing 35 for shipment.

The chimney-cap A is preferably made of four separate sheet-metal side sections, A' A² A³ A⁴, which are riveted together at their beveled ends to form a rectangular cap or cover, 40 having inclined side walls, the cap being supported and anchored to a chimney-top by four corner-clamps, B, one at each chimney-corner and in the angles of the cap. The side sections may be made of cast metal or other 45 desired material; but I prefer to cut them from sheet metal and in substantially the form shown in Fig. 5. The upper edge, a, of each blank is bent over along the broken line x, Fig. 5, to produce a downwardly-projecting 50 flange. These flanges form the sides of the mouth of the chimney-flue, as shown in Fig.

3. The edge a' on one of the beveled or diagonally-cut ends of the blanks is bent over along the broken line y to produce an overlapping flange adapted to overlap the contiguous end of an adjoining side, as shown in Fig. 2.

Fig. 6 represents the appearance of the blank as seen in Fig. 5 after the edges a and a' have been bent over to form the required flanges.

The side pieces can be made of any desired length to fit different-sized chimneys.

As shown in Figs. 1, 2, and 3, the two longer sides of the chimney are two and one-half bricks long, while the other two sides or ends are one and one-half brick long. The side pieces A² are therefore designed for chimney-sides one and one-half brick long, A⁵ for sides two bricks long, A' for sides two and one-half bricks long, and A⁶ for sides three bricks long.

The side pieces are all made alike except in length, those of the same length being interchangeable.

The sides can be easily and closely packed together in a detached condition for shipment, as shown in Fig. 7, and need not be riveted or clamped together until they reach the chimney. The corner-clamps B are all made 80 alike and serve to anchor the cap upon the chimney-top.

The clamp consists of two right-angular vertical sides, B' and B², which are inclined at their upper ends at B³ and B⁴ to form a support for the inclined corners of the cap. The vertical sides are connected by and support a fluke, B⁵, adapted to be anchored on top of the corner-brick in an intermediate course of bricks forming the chimney-top D. The inclined part is provided with a slot, B⁶, adapted to receive a bolt, b, which is passed down through the perforated angle-plate d and through bolt-hole a³ in the side section, as shown partly by dotted lines in Fig. 3.

The cap can be easily secured to an old chimney already erected, or to a chimney during the process of erecting the chimney, as follows: to a new chimney by placing a corner-clamp, B, upon each corner of the chimney, so that the fluke B⁵ rests on top of the corner-brick immediately after the course

marked C in Figs. 1 and 3 has been laid; then laying two more courses of brick, the corner-bricks being laid on top of the fluke B⁵; then placing the cap (made up of four of the side sections of the proper length riveted together by rivets e, passed through the rivet-holes a³) upon the inclined portion of the supporting-clamps so that the bolt-holes a³ are in line with the slots B⁶, placing the angle-plates d upon the cap-corners with their central perforations in line with the bolt-holes a³; then inserting the screw-bolts b and screwing up the nuts b' on the inside until the cap-sections are tightly clamped together between the plate d and the clamps B. When the parts are so clamped together, the cap-sections are not only held tightly together and in place, but the corner-clamps are held tightly clamped against the corner of the chimney by the cap, so that it is impossible for the flukes B⁵ to work out from between the corners of bricks. The chimney-top is then completed by filling in the broken courses C' and C².

25 To attach the cap to an old chimney-top, it is only necessary to clear away from between the courses of brick at the corners of the chimney and two courses down from the top sufficient mortar to admit of the insertion of the thin fluke B⁵, set up the corner-clamps, attach the cap, and top out with the broken courses C' and C², as before described.

I am thus able to easily and cheaply provide chimney-tops with caps which are not only ornamental in appearance, but materially protect the chimney from rain, snow, and ice. I also produce an improved draft of air through the chimney in aid of combustion.

Whatever the direction of the wind may be 40 it strikes the beveled or inclined sides of the cap surrounding the mouth of the chimney-flue and is thrown upward instead of downward, thereby increasing the upward current within the mouth of the chimney-flue.

The slot B⁶ in the inclined ends of the corner-clamps insures an easy fit of the cap upon the clamps after they have been anchored upon the chimney-corners.

Should chimney-tops of the same number of bricks in width and length vary slightly in size on account of variation in amount of mortar used, the bolt-holes a³ and a⁴ will readily accommodate themselves to some part of the slots B⁶, so that the clamping-bolts b may be easily inserted and secured in place.

55 The cap can be secured to the chimney-top in any known manner without any corner-clamps, as by nails driven through the bolt-holes a³, or by cementing the same to the chimney-top.

The flanged plates form a complete article 60 of manufacture which may be put upon the market in a detached condition and set up, as above described, when and as desired.

What I claim as new, and desire to secure by Letters Patent, is—

65 1. A chimney-cap formed of metal plates having on their upper edges an introverted flue-flange and on their ends diagonal lapping edges, which edges are fastened together, as by rivets, substantially as described.

70 2. A chimney-cap plate having along its upper edge a flue-flange, a, and diagonal to such flange lapping end edges, one of the end edges, a', being in the form of a flange angular to the body of the plate, substantially as described.

75 3. The combination, with a rectangular chimney-cap, of corner-clamps B, provided with a fluke, B⁵, and clamped to the cap-corners, substantially as described.

80 In testimony whereof I have hereunto set my hand this 18th day of August, 1888.

ADAM E. CLUTE.
